UNITED STATES PATENT OFFICE.

JOHN E. WHITE, OF ROCHESTER, NEW YORK.

DEVICE FOR REMOVING HAIRS.

1,071,978.

Specification of Letters Patent.

Patented Sept. 2, 1913.

Application filed April 11, 1912. Serial No. 690,070.

To all whom it may concern:

Be it known that I, JOHN E. WHITE, a citizen of the United States, residing at Rochester, in the county of Monroe and 5 State of New York, have invented certain new and useful Improvements in Devices for Removing Hairs; and I do declare the following to be a full, clear, and exact description of the invention, such as will enable others skilled in the art to which it 10 appertains to make and use the same.

This invention relates to improvements in devices for removing superfluous hairs and destroying the roots thereof.

15 One object of the invention is to provide a device of this character by means of which superfluous hairs may be effectively removed without pain to the patient.

Another object is to provide a hair 20 remover which will be simple and inexpensive in construction, efficient and reliable in operation and which when not in use as a hair remover may be employed as an ordinary pair of tweezers.

25 With these and other objects in view, the invention consists of certain novel features of construction, and the combination and arrangement of parts as will be more fully described and claimed.

30 In the accompanying drawings, Figure 1 is a side view of my hair removing device; Fig. 2 is a central vertical longitudinal section thereof; Fig. 3 is a cross sectional view of the same on the line 3—3 of Fig. 2; Fig. 35 4 is a similar view on the line 4—4 of Fig. 2; Fig. 5 is a detail cross sectional view through one of the insulating blades of the device on the line 5—5 of Fig. 2.

My improved hair removing device is in 40 the form of a pair of tweezers and comprises blades 1 which are slightly curved at their outer ends and are spaced apart at their inner ends by a block 2 of suitable insulating material. The blades 1 are firmly 45 secured to the block 2 by a connecting bolt 3 which is insulated from the blades by a sleeve 4. The bolt 3 is provided on one end with a suitable head and on its other end has a clamping nut 5 as shown.

50 The blades 1 are covered on their outer sides and edges by a casing or covering 6 of suitable insulating material secured to the blades by brass pins 7 which pass through the blades and through the edges of the 55 insulating covering 6 as shown. The casing or covering 6 of the blades extends to

within a short distance of the outer ends of the points 8 of the blades, said points being left exposed to permit the same to make contact with the flesh around the hair to be 60 removed.

At the outer end of the tweezers and having an electrical connection with the blades 1 are eyes or sockets 9 adapted to receive plugs or terminals 10 of electrical current 65 conducting wires 11 whereby a current of electricity is applied to the blades and is conducted by the same to the points thereof, the current passing from the points of the blades through the cuticle around the hair, 70 thereby benumbing the flesh at this point where it is extremely sensitive or at least is so considered by the patient. In applying the electric current in this manner the operation will be practically painless and 75 the danger of scars resulting from the operation is entirely obviated. By disengaging the terminals 10 of the electric conductors from the sockets or eyes 9 the device may be employed as an ordinary pair of 80 tweezers.

From the foregoing description taken in connection with the accompanying drawings, the construction and operation of the invention will be readily understood without requiring a more extended explanation. 85

Various changes in the form, proportion and the minor details of construction may be resorted to without departing from the principle or sacrificing any of the advantages of the invention as claimed. 90

Having thus described my invention, what I claim is:

1. A hair removing device comprising a pair of tweezers whose blades are insulated from each other and are insulated on their outer sides to within a short distance of their free ends, and means for connecting the blades respectively with the terminals of an electric circuit. 95

2. A hair removing device comprising a pair of tweezers whose blades are insulated from each other and are insulated on their outer sides to within a short distance of their free ends, socket members respectively connected with said blades and insulated from each other, and plugs removably fitting in the sockets and respectively connected with the terminals of an electric circuit. 105

3. A hair removing device comprising a pair of blades, an insulating block between 110

them at their upper ends, a bolt passing through the blades and blocks, an insulating sleeve surrounding the bolt, an insulating covering on the outer side of each blade throughout its length and extending to a point near its lower end, the covering passing over both edges of the blades, pins passing edgewise through the latter and engaging the edges of said covering, and means for connecting the blades respectively with the terminals of an electric circuit.

4. A hair removing device comprising a pair of blades insulated from each other, an insulating covering on the outer side of each

blade throughout its length and extending to a point near its lower end, the covering passing over both edges of the blades, pins passing edgewise through the latter and engaging the edges of said covering, and means for connecting the blades respectively with the terminals of an electric circuit.

In testimony whereof I have hereunto set my hand in presence of two subscribing witnesses.

JOHN E. WHITE.

Witnesses:

H. HENRY,

ALEXANDER M. KESSELRING.
